SAFETY DISPENSING NOZZLE

Elbert R. Sitton, Houston, and Charles J. Crassons, Fort Worth, Tex.

Application September 16, 1939, Serial No. 295,162

10 Claims. (Cl. 226—127)

The invention relates to nozzles such as are employed in dispensing gasoline or similar liquid.

It is an object of the invention to provide a nozzle of this character which will automatically shut off the discharge of liquid from the nozzle when the receptacle into which the liquid is discharged has reached a certain level.

It is a further object to provide means for controlling said nozzle adapted to shut off the discharge of liquid when the position of the nozzle has been disturbed, as, for example, when the receptacle is moved relative to the nozzle.

It is another object of the invention to provide means to regulate the rate of discharge of liquid from the nozzle to avoid the discharge of liquid at an excessive rate.

It is a further object of the invention to provide a means for controlling the discharge of liquid which is adapted for use in various types of receptacles into which the liquid is discharged.

It is a further object of the invention to provide means of unseating the valve at the discharge end of the nozzle manually when said valve is stuck in its seat.

Various other points of novelty connected with the particular construction and arrangement of the parts of the assembled device are present in the improved type of nozzle and will be more clearly understood in connection with the drawing herewith.

In the drawing, Fig. 1 is a central longitudinal section through a nozzle constructed in accordance with this invention.

Fig. 2 is a side elevation thereof.

Fig. 3 is a detail of the automatic valve showing the same as extending within the inlet to a gasoline tank.

Fig. 4 is a transverse section on the plane 4—4 of Fig. 1.

Fig. 5 is a broken side elevation showing the rotatable ring whereby the discharge openings may be regulated.

The improvement is adapted to be used upon discharge nozzles of various types and may be used as an attachment for old nozzles now in existence or may be constructed as a unitary device to be sold as a complete unit.

In the drawing is shown a body 1 which has a threaded end 2 for connection with the hole or pipe 3 leading to a container for liquid such as gasoline. The body 1 is provided with a valve chamber 3' having a transverse partition 4 therein with a valve-receiving opening 5. Within said opening is a valve 6 mounted upon a stem 7 which extends at one end through the wall of 55

the valve chamber and projects at 8 from the stuffing box 9 on said wall. The projecting end 8 is adapted to be depressed by a lever arm 10 pivoted at 11 in the outer wall of the chamber.

15 The valve also has a guide stem 12 fitting within a guide member 13 and a spring 14 is employed to hold the valve normally in closed position. It will be seen that the valve stem 8 when depressed will unseat the valve and allow the passage of liquid. This is no part of the present invention.

At the discharge end from the valve chamber is secured a discharge nipple 15. Said nipple is screwed within the end of the valve chamber and is curved so as to more easily be fitted within the 20 end of the neck 16 which is understood as being connected with a receiving tank such as the gasoline tank upon a motor car.

The end of the nipple 15 is reduced in diameter adjacent its end remote from the valve chamber and threaded for connection within a 25 coupling 17. Said coupling serves as a connection with a flexible float chamber 18 secured thereto.

Between the coupling member 17 and the end 20 of the discharge nipple is a rotatable sleeve or collar 20. Said collar has a plurality of lateral openings 21 therein through which liquid from the interior may pass outwardly.

The forward end 19 of the nipple 15 has its 30 interior passage tapered inwardly toward the passage within the nipple thereby providing the generally tapered seat indicated at 22 into which may fit a tapered valve member 23.

There are lateral openings 24 in the tapered seat member which may be brought into registration with the openings 21 in the rotatable sleeve through the rotative movement of said sleeve.

Housed within the coupling member 17 is a 35 diaphragm or plate 25, which tends to close the end of the discharge member. Said plate 25 has a central opening 26 therein through which a valve stem 27 is extended. Said stem is connected at one end, as shown at 28, to the valve member 23. This will be seen best in Fig. 3.

40 The other end of the valve stem 27 which projects outwardly through the plate 25 is rounded at 29 to contact with the innermost of a plurality of spherical float members 30. Proximate the upper end of the chamber 18 and beneath the plate 25 there are provided a plurality of radial openings 48 which prevent air lock of the float members as liquid moves upwardly within such chamber.

45 The flexible end member 18 upon the nozzle is preferably made from a spiral winding of sheet

metal, as shown best in Fig. 2, the end of which is reenforced by a ring of sheet metal 31.

Within this flexible member are the float members 30 and it is contemplated that a plurality of said floats will be employed each placed in contact with the adjacent one and arranged so that the outermost float member will fit against a shoulder 32 upon the ring 31, thus holding the floats from being moved out of the housing.

When the valve 23 is in closed position, as shown in Fig. 3, it sometimes adheres to its seat and fails to drop back into open position when the flow of the liquid is stopped. In such cases a rod 33 is used to exert pressure against the valve to unseat it. At the forward end of the rod 33 is a contact member 34 which may engage with the valve to unseat it, said contact member having lateral shoulders 35 which limit its movement downwardly against the valve. The outer end of the stem 33 is connected with a push button 36 which projects through a stuffing box 37 in the side wall of the nipple 15. A spring 38 normally holds the push button extended outwardly and it will be understood that when the push button is released the spring will withdraw the stem outwardly away from the valve.

In order that the valve 6 may be automatically held in open position there is a lever arm 39 constructed in U-shape, as shown in Fig. 4, with the ends thereof secured upon a pivot member 40 which, as shown in Fig. 1, is supported on the lower side of the nipple 15. It is extended through a supporting collar formed upon a plate 41 secured upon said nipple by welding or other equivalent means. This U-shaped arm is adapted to engage with the underside of the lever arm 42, which operates the valve. There is an oppositely extending U-shaped arm 42 mounted upon the pin 40. The forward end of this arm is curved slightly to engage beneath the inner flange 43 upon the neck 44 of the tank. With this device it will be understood that when the nozzle is inserted within the neck 44 of the tank the forward arm 42 will engage beneath the rim 43 and move the opposite arm 39 upwardly against the valve operating arm 19 and open the valve. Should the tank be moved relative to the nozzle, as when the vehicle is moved away from the nozzle, the lever 42 will be released and the arm 39 will drop to allow the valve to close, thus shutting off the discharge of gas.

In the normal operation of the nozzle the forward end thereof will be inserted into the gasoline tank or other similar receptacle with the forward float chamber 18 extending into the neck of the tank. The end 42 of the control lever will be engaged beneath the flange 43, as shown in Fig. 2, thus causing the opposite arm to open the valve, allowing the discharge of gasoline or other liquid. If the valve 23 is closed and will not readily unseat to allow the discharge of liquid through the openings 21 and 24, the push rod 33 may be operated to release the valve. Gasoline will then be discharged through the openings 21 and 24 into the neck of the tank. The size of the opening through which the liquid is discharged will be regulated as shown in Fig. 5. The sleeve 20 is rotated relative to the inner end of the nipple so that the resulting opening shown at 46 in Fig. 5 will be sufficient to allow the liquid to be discharged at the proper rate. The sleeve 20 may be fixed in this position by means of set screws 47.

When the valve 23 is in open position the end

of the stem 27 will contact with the float members 30 in the float chamber. It has been found that when the discharge of gasoline or semi-liquid from the nozzle is at an excessive rate such that the passage through the openings 21 will not freely receive it the valve 23 will begin to close. Discharge of the liquid at an excessive rate is undesirable as it causes the liquid to overflow at the upper end of the neck even though the tank is only partially full. The flow from the nozzle through the openings 21 causes a reduction of pressure adjacent the valve 23 sufficient to cause it to be moved toward closed position, thus throttling the flow of liquid and in case the flow is sufficiently rapid the valve may be entirely closed until the rate of flow has been reduced.

When the tank has been sufficiently filled so that the float members 30 are gradually submerged, as shown in Fig. 3, the point will be reached where the buoyancy of the float members will raise the valve 23 to closed position, as shown in that figure. Thus the discharge of gasoline will be automatically shut off when the tank has been filled to the desired amount. It will be obvious, of course, that a further amount of gasoline may be discharged into the tank through the use of the hand-operated valve control member 33. When the nozzle is then withdrawn from the tank the lever arm 42 will be released and the valve 6 will automatically close.

The float chamber as here constructed is flexible and may be bent to conform to the passage into which it is inserted. The floats, being separate members, will be able to move in said chamber even where it is curved. It is thus assured that the floats will act, when submerged, to bear against the stem 27 and move the valve in spite of any curvature of the flexible chamber.

It will be seen that the nozzle constructed as described will be automatic in its action so that the personal attendant in a filling station may start the flow of gas and then busy himself with other duties, while the tank is being filled. The nozzle will provide for the automatic shutting off of the gasoline as soon as the tank has been filled to the desired level. It will thus be seen that an automatically controlled discharge member has been provided which will assure the operator that the flow of gasoline from the nozzle will be shut off before any overflow of gasoline from the tank can take place. The advantages of this construction will be obvious to those skilled in the art.

What is claimed is:

1. A dispensing nozzle including a pipe, a manually operated valve therein, a discharge nipple, an inwardly tapered valve seat therein with lateral openings, a tapered valve within said nipple forwardly of said opening, a forwardly extending stem on said tapered valve, and a float member coacting with said stem to move said valve into engagement with said tapered seat.

2. A dispensing nozzle including a pipe, a manually operated valve therein, a stem on said valve, an operating arm adapted to engage said stem, means adapted to be moved by contact with a container to move said arm to open said valve, a discharge nipple, an inwardly tapered valve seat therein with lateral openings, a tapered valve in confronting relation with and movable relative to said seat, a stem on said tapered valve, and a float member coacting with said stem to

move said valve into engagement with said tapered seat.

3. A dispensing nozzle including a discharge nipple having lateral openings therein, means to regulate the size of said openings, a valve movable to and from position closing said openings, a stem on said valve, a cylindrical float chamber attached to said discharge nipple, a plurality of spherical float members in said chamber, said members being movable when submerged in liquid to contact said stem and close said valve.

4. A dispensing nozzle including a discharge nipple, an inwardly tapered seat in the outlet end thereof, said seat having lateral openings therein, a valve member tapered to fit said seat, a flexible float member extending beyond said valve, a plurality of separately movable float members therein, and means on said valve to contact one of said float members and move said valve.

5. In a dispensing nozzle, a discharge nipple, a valve movable to open and close said nipple to control the discharge of liquid from said nipple, a flexible cylindrical float chamber at the free end of said nipple, a plurality of spherical float members in said chamber, and means on said valve to contact one of said float members to move said valve.

6. In a dispensing nozzle, a discharge nipple, a valve movable to open and close said nipple to control the discharge of liquid from said nipple, a flexible cylindrical float chamber at the free end of said nipple, a plurality of superposed float members in said chamber, a stem on said valve projecting therefrom to contact with one of said float members when said members are moved upwardly.

7. In a dispensing nozzle, a discharge nipple having an outlet, an inwardly tapered seat at

said outlet, a valve in the nipple outwardly from the seat movable to and from said seat to close or open said outlet, float operated means to close said valve, a push rod in said nipple adjacent said valve, positioned to be moved to unseat said valve and means to limit the movement of said rod.

8. A dispensing nozzle including a valve body, a discharge nipple thereon, a valve in said body movable to close the passage therethrough, a stem on said valve projecting from said body, a lever to contact with said stem to move said valve, an arm pivotally mounted on said nozzle adapted to engage a container at one end whereby the other end is swung into position to move said lever to open said valve.

9. A dispensing nozzle including a discharge nipple having a passage with lateral openings in the sidewalls thereof, a valve movable against the flow of liquid through the nipple to and from position closing said openings, a float chamber beyond said valve, a stem on said valve extending into said chamber, float means in the chamber adapted to move said stem and close the valve and means manually operable from the exterior of the nipple for opening said valve.

10. A dispensing nozzle including a discharge nipple having a passage with lateral openings in the sidewalls thereof, a closure plate in the passage beyond said openings, a valve movable to and from position closing the openings, a float chamber beyond said closure plate, a stem on said valve passing slidably through said plate and into said float chamber, and float means in said chamber adapted to move said stem and close said valve as liquid rises within the float chamber.
